UNITED STATES PATENT OFFICE.

HENRI PERREGAUX, OF LAUSANNE, SWITZERLAND.

PROCESS OF GRAPHIC REPRODUCTION.

1,365,058.

Specification of Letters Patent. Patented Jan. 11, 1921.

No Drawing.

Application filed April 22, 1920. Serial No. 375,819.

To all whom it may concern:

Be it known that I, HENRI PERREGAUX, citizen of Switzerland, residing at Lausanne, Switzerland, have invented certain new 5 and useful Improvements in Processes of Graphic Reproduction, of which the following is a specification.

This invention consists in a process of graphic reproduction in which are employed 10 blocks or negatives comprising a plate of glass on which the design is formed as a metallic deposit adhering strongly to the glass. The reproduction is effected by means of printing ink which contains glycerin, 15 and the design can subsequently be removed from the plates by means of an acid so thoroughly that the plates are readily susceptible of re-use. The metallic deposit in question is preferably obtained by moistening 20 the plate and rubbing thereon a metal stylus which preferably consists of aluminium or an alloy of aluminium. If necessary, the relief may be accentuated by hollowing out the ground work by means of an acid 25 which attacks glass.

To prepare a negative according to the process which forms the subject of the invention, I may proceed for example, as follows:—

30 The edges of a smooth ground glass plate are chamfered, and after the surface of the plate has been moistened with water, the design to be reproduced is drawn thereupon by means of an aluminium stylus. The 35 aluminium stylus leaves on the plate a mark which consists of a metallic deposit of aluminium adhering very strongly to the glass. The glass face in question is then dried, and inked by means of ordinary 40 printing-ink containing, however, a certain proportion of glycerin, the introduction of this substance in the composition of the ink giving it a quality of not adhering to the glass but only to the metallic deposit which 45 forms the design.

If it is desired to have the relief of greater height than that of the metal deposit, the ground work between the lines can be hollowed out by means of hydrofluoric acid, 50 which attacks the glass wherever it contacts. This may be applied with a brush, or

I may alternatively cover all the plate with a film of wax, and remove the wax where desired and then expose the plate to the vapors of hydrofluoric acid.

55

The block or negative obtained by the process according to this invention is permanent, and can be made much cheaper than zinc blocks or blocks of composition obtained by the mechanical processes usually 60 employed in reproducing a design which has first to be traced on paper. Manipulation and electro-chemical baths are avoided, and as the original design is reproduced, the 65 block follows faithfully the idea of the artist.

Negatives or blocks thus obtained can be used either for hand-printing by the aid of ink rollers or for machine-printing in ordinary presses. In the latter case, I may use 70 either a number of relatively thin plates mounted upon a wooden stand with the interposition of a bedding of elastic material such as rubber, or I may directly employ glass blocks sufficiently thick to be gripped 75 without other supports in the form of the press. These thick glass blocks may be formed integral or may consist of plates superposed and united by adhesives and can easily be made of such a thickness of glass 80 as resists the usual pressures to which blocks are submitted in the big modern presses. The glass blocks may be adapted for re-use by washing with an acid, such as sulfuric or hydrofluoric, employing a suitable mop 85 so as to erase the design. I find that it is possible to obtain reproductions on any paper so well that the blocks can be used in combination with letter-press: and they can further be adapted for color reproduction 90 according to the usual principles of the employment of polychrome blocks.

Claim.

The herein described process of graphic reproduction, consisting in moistening a 95 glass plate with water, drawing the design thereon by means of an aluminum stylus, drying the glass plate, inking the design by means of a printing ink containing glycerin, and utilizing the plate so prepared for print- 100 ing impressions of the inked design.

HENRI PERREGAUX.
